LOG LIFTER AND HOLDER

Filed Nov. 18, 1930

UNITED STATES PATENT OFFICE

WASHINGTON B. PARRISH, OF KENBRIDGE, VIRGINIA, ASSIGNOR OF ONE-HALF TO ROBERT B. PARRISH, OF NASSAWADDOX, VIRGINIA, AND ONE-HALF TO THOMAS W. FOWLKES, OF VICTORIA, VIRGINIA

LOG LIFTER AND HOLDER

Application filed November 18, 1930. Serial No. 496,459.

In the logging industry, the trees, after being felled and stripped of their limbs, are cut up into logs of the required length. This cutting is generally effected by a drag or other form of saw. It frequently happens that the log sags and results in a binding of the saw.

The present invention provides a device which admits of a log being readily lifted and held in elevated position, thereby preventing binding of the saw.

The invention furthermore provides a log lifter and holder which may be easily manipulated by one person and which is adjustable to meet different conditions encountered in preparing timber for market.

The invention also relates to the provision of a device of the character aforesaid which is adapted for use as a cant hook as well as a log lifter, without necessitating any change, removal or adjusting of the parts, thereby saving time and obviating the necessity of providing a cant hook in addition to a log lifter.

While the drawings illustrate a preferred embodiment of the invention, it is to be understood that in adapting the means to meet specific needs and requirements, the design may be varied and changes in the minor details of construction may be resorted to within the scope of the invention as claimed without departing from the spirit thereof.

For a full understanding of the invention and the merits thereof, reference is to be had to the following description and the drawings hereto attached, in which:—

Figure 1 is a side view of a log lifter and holder illustrative of an embodiment of the invention, the turn buckle being in section,

Fig. 2 is an enlarged detail sectional view of the lower end of the lever and extension,

Fig. 3 is an enlarged detail sectional view on the line 3—3 of Fig. 1, and

Fig. 4 is an enlarged detail view of the lower end of the prop and foot.

Corresponding and like parts are referred to in the following description and designated in the several views of the drawings by like reference characters.

The numeral 1 designates a lever upon

which the operating parts are mounted. A clip 2 is fitted upon the lever 1 and may be fixed or adjustable, as desired. Hooks 3 and 4 are connected at one end to the clip 2. The hook 3 is fixed, whereas the hook 4 is pivoted. An eye bolt 5 is applied to the lever 1 and engages the shank of the hook 3 and serves in conjunction with the clip 2 to firmly connect the hook 3 to the lever. The shank of the hook 3 is straight so as to lie close against the lever 1. A bolt 6, or analogous fastening, secures the clip 2. To admit of adjustment of the clip 2 along the lever 1, the latter is provided with a plurality of openings 7 through any one of which the fastening 6 may be passed to secure the clip 2 in the desired adjusted position. The hook 4 may function independently of the hook 3 or jointly therewith accordingly as the log is to be rolled or elevated.

A metal tip 8 is secured upon the lower end of the lever 1 and serves as reinforcing and strengthening means therefor. A section 9 is slidable upon the tip 8 and admits of lengthening or shortening the lever, as may be desired, to properly position the hooks for effective cooperation with the log to be lifted. Suitable fastening means 10, such as clamp screws, are applied to the section 9 and hold it in the required adjusted position. The inner ends of the clamp screws 10 are pointed so as to bite into the metal tip 8 and prevent possible displacement of the section 9 when made secure in the desired adjusted position.

A prop or leg is associated with the lever 1 and is pivotally and adjustably connected thereto. This prop or leg comprises an upper section 11 and a lower section 12, said sections being adjustably connected by means of a turn buckle 13. The prop or leg is provided with a foot 14 which is pivoted thereto so as to adapt itself to the surface condition with which the foot may be engaged when the device is in service. A clip 15 is mounted upon the lever 1 and is connected thereto by means of a bolt 16 or like fastening. A plurality of openings 17 are formed in the length of the lever 1 to receive the fastening 16, thereby providing for securing the clip in the required adjusted position. The prop or leg

is pivotally connected to the clip 15 and is adjustable therewith.

In the operation of the device as lifting and holding means for a log, it is observed that the lower end of the lever 1 is engaged with the ground adjacent the log to be elevated, after which the hook 4 is moved away from the hook 3 to admit of the log passing between the hooks. When the device is adjusted, the lever is inclined and upon moving the same to an upright position, the hooks bite into opposite sides of the log and, as the lever is operated, the log is lifted and is held in elevated position by moving the lower end 15 of the prop or leg so that the latter will maintain the lever in adjusted position with the log elevated a distance from the ground. The broad extent of the pivoted foot 14 enables the prop or leg to obtain positive engagement with the ground without slipping or burying therein. In the event of the log being excessively heavy, it is possible to lift the same by turning the part 13 whereby to lengthen the prop or leg with the result that 20 the lever 1 is positively moved to effect lifting of the log, as will be readily understood. The turn buckle 13 may be rotated by passing a bar or other implement through the frame and utilizing the same in the capacity of a lever. It will be readily understood that the device is adapted for use as a cant hook for rotating a log by utilizing the lever 1 and pivoted hook 4 in a manner well understood.

Having thus described the invention, I 25 claim:

1. A log lifter comprising a lever, a clip adjustable thereon, a hook attached at one end to the clip and formed with a straight shank lying close against the lever, a fastening applied to the lever and engaging the straight shank of the hook which is adapted to slide relatively thereto, and a companion hook pivoted to said clip.

2. A log lifter and holder comprising a lever, log engaging hooks thereon, and a prop pivoted to the lever and adapted to hold the same in required adjusted position.

3. A log lifter and holder comprising a lever, log engaging hooks thereon, and an extensible prop pivotally connected to the lever for supporting the same in the required adjusted position.

4. A log lifter and holder comprising a lever, log engaging hooks thereon, and an extensible prop pivotally and adjustably connected with the lever.

5. A log lifter and holder comprising a lever, log engaging hooks thereon, a prop pivotally connected with the lever, and a foot pivotally connected with the lower end of the prop.

6. A device of the character specified comprising a lever, log engaging hooks thereon, 65 and a section adjustably connected to the

lower end of the lever to admit of varying its length.

7. A log lifter and holder comprising a lever, log engaging hooks thereon, a sectional prop pivotally connected to the lever, and a turn buckle connecting the sections of the prop.

In testimony whereof I affix my signature.

WASHINGTON B. PARRISH. [L.S.]
